UNITED STATES PATENT OFFICE.

FRANÇOIS HENNEBIQUE, OF PARIS, FRANCE.

SLEEPER FOR USE ON RAILWAYS OR THE LIKE.

SPECIFICATION forming part of Letters Patent No. 641,697, dated January 23, 1900.

Application filed July 21, 1899. Serial No. 724,700. (No model.)

To all whom it may concern:

Be it known that I, FRANÇOIS HENNEBIQUE, a citizen of the Republic of France, residing at 54 Boulevard St. Michel, Paris, France, 5 have invented certain new and useful Improvements in or Relating to Sleepers for Use on Railways or the Like; and I do hereby declare the following to be a full, clear, and exact description of the invention, such as will 10 enable others skilled in the art to which it appertains to make and use the same.

The improvements which I have introduced in the construction of sleepers proper of strengthened beton and which form the object of the present application, combined with the method of fixing the rails, which forms the object of another application filed by me for Letters Patent of the United States, dated July 21, 1899, Serial No. 724,701, avoid all the difficulties which prevent the use of strengthened cement beton for constructing railway-tracks.

The characteristics of my invention are as follows: My sleepers have a form which insures their perfect connection with the ballast. They are arranged to act as a support for the rails and prevent spreading or widening of the track. Finally, the judicious distribution of the iron skeleton or strengthening in the mass of cement insures to them a 25 resistance to the various strains to which they are subjected by the passage of trains over the rails. In principle I give the sleeper the form of a reversed T (L) or even the form of a double T laid on its side (I-I), so as to have 30 a large flat horizontal area, forming a dish, and on this area one or two vertical parts are placed, the ballast accumulating on the horizontal wings or flanges around the vertical wings, which serve it for support, and thus 35 preventing the sleeper from turning or moving in the direction of the track. In case a double horizontally-laid T (I-I) shaped sleeper is employed the ballast bears on the two faces of the horizontal area. Each of the vertical skeletons of the sleeper is formed like a 40 strengthened cement girder and arranged according to the principles explained in one of my prior patents. To sum up, the sleeper is formed of one or more beams connected on a 45 flat area, forming a dish, the whole forming a monolith and allowing the ballast to ac-

cumulate on the sleeper instead of merely enveloping the latter. In case the core is used of the shape of a double T laid on its side the sleeper is formed by twin beams or 55 twin girders connected by a flat area.

In the accompanying drawings I have shown as an example two forms of sleepers arranged according to the principles hereinbefore enumerated.

Figures 1 to 5 represent a sleeper in the form of a reversed T (L)—that is to say, formed by a girder resting on a flat area, forming a dish and serving for the accumulation of ballast. Fig. 1 is a longitudinal elevation of a half- 65 sleeper; Fig. 2, a corresponding plan view. Figs. 3, 4, and 5 are transverse sections, respectively, on the lines 3 3, 4 4, and 5 5 of Figs. 1 and 2. Figs. 6 and 7 show, respectively, in longitudinal section and partial 70 plan view, a half-sleeper in the form of a double T laid on the side, Fig. 6 being a section on line 6 6 of Fig. 7. Figs. 8 and 9 are transverse sections, respectively, on the lines 8 8 and 9 9 of Fig. 6.

The vertical skeleton or core V, forming the beam, is strengthened by means of two longitudinal iron bars F F', connected by stirrup-shaped pieces E. The immovable connection between the skeleton or core V and the part H for forming the monolith is insured by horizontal stirrup-shaped pieces E' E''. The horizontal area may be strengthened, particularly at those points where it will undergo the greatest strains—that is to say, toward the 85 ends and in the parts adjacent to the rails—by irons R R'. The rail rests on an enlarged part, forming the shoulder C, against the core or skeleton V. This partitioning of the reversed-T-shaped tapered core where the rails 90 pass further increases the facility of retaining the sleeper against lateral displacements. The core or skeleton V is hollowed out or recessed at e, the lateral faces e' e'' of the recess forming a shoulder for the support of the devices for keying and fixing the rail.

Referring to Figs. 6, 7, 8, and 9, the vertical parts or wings are formed of two girders of strengthened cement V' V'', connected by a flat area H', forming a dish for holding ballast and serving for retaining or anchoring this latter. The constitution of the girders

V' V^2 is according to the principles hereinbefore mentioned, and the formation of the block or monolith is insured by means of iron bars R or stirrup-shaped horizontal pieces 5 suitably distributed. The rail r always rests in a recess, which in this whole arrangement is obtained by a groove, enabling the area H' to be employed as a surface for the support of the rail. Partitions C C' serve as shoulders 10 and strengthening-pieces and also for preventing the lateral displacement of the sleeper.

I claim—

1. A composite sleeper comprising a horizontal base portion, a vertical portion having bearing-shoulders for the rails, rods at the 15 top and below said vertical portion, and stir-

rup-shaped pieces connecting said rods, substantially as described.

2. A composite sleeper comprising a horizontal base portion, a vertical portion having 20 bearing-shoulders for the rails, rods at the top and below said vertical portion, and stirrup-shaped pieces connecting said rods and the horizontal stirrups embedded in said horizontal portion and engaging the lower rod, 25 substantially as described.

In witness whereof I have hereunto set my hand in presence of two witnesses.

FRANÇOIS HENNEBIQUE.
